(57) **CLAIM**

The ornamental design for an electrode, substantially as shown and described.

DESCRIPTION

FIG. 1 is a perspective rear view of an electrode.

FIG. 2 is an exploded view of the electrode of FIG. 1.

FIG. 3 is a rear view of the electrode of FIG. 1.

FIG. 4 is a front view of the electrode of FIG. 1.

FIG. 5 is a left side view of the electrode of FIG. 1.

FIG. 6 is a right side view of the electrode of FIG. 1.

FIG. 7 is a bottom view of the electrode of FIG. 1; and, FIG. 8 is a top view of the electrode of FIG. 1.

The evenly spaced broken lines in each figure illustrate features of the electrode that form no part of the claimed design. The dash-dot-dot-dash broken lines depict boundaries of the claimed design and form no part thereof.
